US00D567692S

(12) **United States Design Patent** (10) **Patent No.:** **US D567,692 S**
Meyers et al. (45) **Date of Patent:** **** Apr. 29, 2008**

(54) **DISPLAY DOORBELL CHIME COVER**

(75) Inventors: **David O. Meyers**, Kaysville, UT (US);
Alfredo D. Carreno, Aurora, IL (US);
Suzanne M. Loose, Pewaukee, WI (US)

(73) Assignee: **Broan-NuTone LLC**, Hartford, WI (US)

(**) Term: **14 Years**

(21) Appl. No.: **29/221,358**

(22) Filed: **Jan. 13, 2005**

(51) **LOC (8) Cl.** **10-05**

(52) **U.S. Cl.** **D10/118**

(58) **Field of Classification Search** D6/300, D6/441, 446; D8/353, 16; D10/116, 118, D10/121; D23/366; D26/26, 85, 87, 118; 116/141, 148; 40/738, 743, 792; D14/214, D14/371-382; D32/46

(57) **CLAIM**

The ornamental design for a display doorbell chime cover, as shown and described.

DESCRIPTION

FIG. 1 is a perspective view of a display doorbell chime cover;

FIG. 2 is a front view of the display doorbell chime cover shown in FIG. 1;

FIG. 3 is a rear view of the display doorbell chime cover shown in FIGS. 1 and 2;

FIG. 4 is a top view of the display doorbell chime cover shown in FIGS. 1-3;

FIG. 5 is a bottom view of the display doorbell chime cover shown in FIGS. 1-4;

FIG. 6 is a right side view of the display doorbell chime cover shown in FIGS. 1-5; and,

FIG. 7 is a left side view of the display doorbell chime cover shown in FIGS. 1-6.

An alternate style of broken line, including alternating long and short dashes, is used to indicate the boundaries of the claimed subject matter and forms no part of the claimed design.

1 Claim, 5 Drawing Sheets
